UNITED STATES PATENT OFFICE.

HILDOR ERICKSON, OF PALMER, IOWA.

ROAD-DRAG.

1,174,483.

Specification of Letters Patent.

Patented Mar. 7, 1916.

Application filed July 31, 1915. Serial No. 43,011.

To all whom it may concern:

Be it known that I, HILDOR ERICKSON, a citizen of the United States, residing at Palmer, in the county of Pocahontas and 5 State of Iowa, have invented a new and useful Road-Drag, of which the following is a specification.

This invention relates to an improvement in road drags, and the object is to provide a 10 frame having a plurality of blades extending outwardly from the sides thereof, and means for adjusting the blades to change the angle of the blades to suit the conditions in the working of the road.

15 A further object is in the provision of gutter or ditch cleaners for the purpose of cleaning the ditches at the same time that the road is being scraped.

A still further object is in the provision 20 of means for conveying the drag from one locality to another by means of wheels or rollers, which are connected to the drag and normally held at an elevation, so that they will not interfere with the drag blades when 25 they are to be used, but which are capable of being lowered for elevating the blades when it is desired to remove the drag from one destination to another without the blades coming in contact with the road surface.

30 The invention consists of certain novel features of construction and combinations of parts, which will be hereinafter described and pointed out in the claims.

It will be evident that many slight 35 changes may be made in the form and arrangement of the several parts to be described, without departing from the spirit and scope of the invention, and hence I do not wish to be limited to the exact construction herein set forth.

In the accompanying drawings,—Figure 1 is a top plan view of the invention, the dotted lines indicating the position assumed by the blades in crowning the road. Fig. 2 45 is a view in end elevation. Fig. 3 is a vertical sectional view on the line 3—3 of Fig. 1. Fig. 4 is a sectional view on the line 4—4 of Fig. 1. Fig. 5 is a detail view partly in section of the clip and pulley of the draft beam, illustrating the manner of passing the 50 blades around the pulley.

The frame of the drag, which is preferably made rectangular, consists of longitudinal channel or I beams A which are connected together by cross-bars 1—1 and diagonal bars 2. The cross bars 1, beams and the diagonal bars 2, afford a strong and rigid frame. Pivotedly connected to the lower surfaces of the beams A are the inner terminals of the transverse or channel bars 3. These bars are preferably made U-shaped, the smooth surface projecting toward the forward end of the machine, and the right-angular flanges 4 extending rearwardly. The upper flanges 4 of the channel bars 3 are connected to the beams A by means of bolts 5 and nuts 6. Mounted on the bars 3, and near their outer terminals, are longitudinal channel beams B. The beams B are connected to the upper flanges 60 of the transverse bars 3 by means of bolts 7 and nuts 8. Braces 9 are connected to the lower flanges 4 of the bars 3 by bolts 10 and nuts 11. The upper terminals of the braces 9 are connected to the undersides of 65 the beams A and B by means of bolts 12 and nuts 13. These braces strengthen the transverse bars 3 along their lower edges where the greatest strain is imparted to the bars. 70

Connected to the front face of each bar 3 80 is a blade 14, by means of bolts 15 and nuts 16. The blades 14 project below the lower terminals of the bars 3. Mounted centrally on each bar A is a vertical shaft 17. The shaft passes through an upper flange 18 of 85 the bar A, and has its lower terminal reduced to fit into an opening 19 in the lower flange 20 of the bar. A washer 21 is mounted upon the shaft beneath the upper flange 18, and a pin 22 passes through the shaft 90 beneath the washer for fastening the shaft to the beam.

Mounted upon the shaft 17, and above the flange 18 of the beam A, is a sprocket wheel 23 which is fixed to and rotatable with the 95 shaft 17. Connected to the outer terminals of each beam B is a chain 24, which chain passes around the sprocket wheel 23 of the shaft 17. Upon the rotation of the shafts 17 the chains 24 will be caused to travel in 100 one direction or another for shifting the transverse bars 3 at an angle to the beams

A. Longitudinal plates 25 are mounted upon bars 1 connected to the beams A. A ratchet wheel 27 is fixed to each shaft 17 and located above the plates 25. A foot 5 pedal 28 is fulcrumed on the plates 25, and a terminal of each foot pedal 28 is adapted to engage the teeth of the ratchet wheels 27 for holding the shafts 17 against rotation, whereby the transverse bars 3 may be held at 10 right angles to the beams A, or at any angle in a horizontal plane which the occasion may demand.

The two shafts 17 and chains 24 permit the bars 3 on each side of the frame to be 15 maintained at the same angle with respect to the frame or beams A, or one set of bars may be held at a different angle from the other set, or the bars on the opposite side of the frame. Connected near each end of 20 the beams A and B are bell crank levers 29. Journalized in the lower terminals of the bell crank levers are rollers or wheels 30. A link 31 is connected to the levers 29 of each beam. A hand lever 32 is pivotally 25 connected to each beam A and B, projects upwardly from the frame, as shown in Figs. 2 and 3, for ready access and is pivotally connected to the link 31 of each beam by a pin 33. A toothed segment 34 is connected 30 to each beam, and the teeth of the segment are engaged by pawls 35 which are connected to the hand grip 36 of the lever 32 by links 37. Upon the actuation of the 35 levers 32 the wheels 30 can be moved to a position for raising the blades 14 above the road surface, or the wheels can be moved to a position so that the blades will be moved into engagement with the road surface and the wheels above the road surface. When 40 the wheels are brought into engagement with the road surface the drag can be moved from one locality to another, across bridges and the like.

When it is desired to cross a bridge which 45 may be of narrow construction, the bars 3 can be swung or shifted at such an angle with respect to the beams A, for instance, that indicated by dotted lines in Fig. 1, so that the drag can be conducted across the 50 bridge without the necessity of disconnecting any of the parts of the drag.

Hinged to the outer surfaces, and near the lower terminals of the beams B, are bars 38 which are provided with blades 39. These 55 bars 38 and blades 39 are constructed and connected together in the same manner as the bars 3. A chain 40 is connected to an eye 41, at the outer terminal of each bar 38, and a hook 42 on the other terminal of the 60 chain is adapted to engage an eye 43 on the bar of the beam B for affording rigidity to the bar 38 during the scraping operation. The bars 38 are intended to scrape or clean the gutters or ditches along the sides of the

road, and the angle of these bars can be 65 changed by simply passing the hook 42 through the eye 43 and causing the hook to engage a link of the chain or the eye 41. When the hooks 42 are passed through the eye 43 and engage the eyes 41, the bars 38 70 will be swung practically to their limit of movement toward the beams B.

A draft beam 45 is provided with clips 46 at its outer terminals, and journaled in the clips are pulleys 47. Chains 48 are connected to the beams A and B and each chain passes around a pulley 47. This flexible connection between the drag and the draft beam permits the drag frame or beams A to 75 always be maintained in the line of draft, whereas the bars 3 and 38 may be at an angle to the line of draft. The connection of the bars 3 with the beams A and B is such that the bars may be swung or shifted to an angle with respect to the beams without changing the parallelism of the beams A and B. The beams B may be moved closer to the beams A, but they will always be maintained in a parallel relation, and the bars 3 will always be maintained parallel 80 to each other. The chains or flexible connections 24 permit the bars on either side of the frame to be shifted at an angle with respect to the frame, regardless of the angle 85 of the other set of bars located on the opposite side of the frame.

From the foregoing it will be seen that I have provided a drag which can be constructed and assembled at a small cost, and which is simple in its operation. The scraper 100 blades can be arranged at any angle to suit the requirements in the formation of the road surface. When the road is to be crowned the bars 3 and the plates 14 are 105 swung at an angle, other than a right angle, with respect to the beams A.

What is claimed is,—

1. A road drag comprising a main frame, lateral frames pivoted for horizontal adjustment on the main frame, scraper blades depending from the lateral frames and adapted for adjustment therewith into various angles with respect to the main frame, manually-operated adjusting means for the lateral frames, and adjustable ditch scrapers 110 projecting outwardly from said lateral frames.

2. A road drag comprising a main frame, road scraper frames hinged to the sides of said main frame, outstanding ditch scrapers 115 carried by the said road scraper frames, and independent adjusting means for the road scraper frames and for the ditch scrapers.

3. A road drag comprising a main frame, road scrapers projecting outwardly from the opposite sides of the main frame, means for 120 adjusting the road scrapers to the desired

angle with respect to the main frame, locking means for retaining the scrapers in adjusted position, ditch scrapers extending outwardly from the road scrapers, and adjustable means for holding the ditch scrapers at the desired angle with respect to the road scrapers.

4. A road drag comprising a main frame, road scrapers outstanding from the main frame, independent adjusting means for the road scrapers, a hand controlled device for actuating each adjusting means and adapted to be operated from above the main frame, and a draft beam adjustably connected to the main frame and to the road scrapers adapted to equalize the load, and at the same time admit of the independent adjustment of the road scrapers.

5. A road drag comprising a frame, bars pivotally connected to the frame at the inner terminals thereof, and at the sides of the frame, said bars having blades thereon, beams connected to the outer terminals of the bars for maintaining them in parallel relation, means connected to the frame and beams for adjusting the angle of the bars, and hinged bars connected to the beams projecting beyond the terminals of the parallel bars, and adjustable means connected to the outer terminals of said bars and to the beams.

6. A road drag comprising a frame, a plurality of transverse bars pivotally connected at their inner terminals to the sides of the frame, said bars having blades thereon, beams connected to the outer terminals of said transverse bar, shafts connected on the frame having sprocket wheels, chains connected to the terminals of the beams and passing around the sprocket wheels, whereby upon the rotation of the shaft the transverse bars may be shifted for changing the angle of the transverse bars with respect to the frame, a draft beam, and flexible means connected to the beams and frame and engaging the draft beam.

7. A road drag comprising a main frame, lateral frames hinged to the main frame, road scrapers mounted on the lateral frames, a draft beam adjustably connected to the main and lateral frames, and manually adjustable means for moving the lateral frames into the desired angle to the main frame without disturbing the line of draft through said draft beam.

8. A road drag comprising a frame, transverse bars pivotally connected thereto at their inner terminals, said bars having blades thereon, beams connected to the transverse bars at their outer terminals, means on the frame and connected to the beams for adjusting the angle of the transverse bars, a draft beam having pulleys journaled thereon at the terminals of the beam, a chain con-

nected to each beam and passing around a pulley of the draft beam and connected to the frame, whereby the draft beam may adjust itself to exert a pulling force from the frame and beams regardless of the position assumed by the beams.

9. A road drag comprising a frame, transverse bars pivotally connected to the frame at the inner terminals thereof and at the sides of the frame, said bars having blades thereon, beams connected to the outer terminals of the transverse bars, ditching bars hinged to the beams at the rear terminals thereof and depending blades thereon, and flexible means connected to the outer terminals of the ditching bars and to the forward ends of the beams for adjustably connecting the ditching bars to the beams, a draft beam, and flexible means connecting the draft beam to the beams and frame.

10. A road drag comprising a frame, a plurality of transverse bars pivotally connected at their inner terminals to the sides of the frame, said bars having blades thereon, beams connected to the bars at their outer terminals, shafts mounted on the frame having sprocket wheels, chains connected to the outer terminals of the beam and passing around the sprocket wheels, whereby the transverse bars may be adjusted at various angles, means on the frame for locking the shafts against rotation, ditching bars hinged to the beams, flexible means connected to the outer terminals of the ditching bars and to the beams, a draft beam flexibly connected to the frame, and means for elevating the bars and frame and conveying them from one destination to another.

11. A road drag comprising a plurality of inner and outer longitudinal beams, a plurality of transverse bars pivotally connected to the inner longitudinal beams, cross and diagonal bars connected to the inner beams for holding said inner beams parallel and relatively stationary, said outer beams being connected to the outer terminals of the transverse bars, means connected to the inner and outer beams for adjusting the transverse bars at an angle to the inner beams, ditching bars hinged to the outer beams, flexible means connecting the outer terminals of the ditching bars to the outer beams, a draft beam, means for flexibly connecting the ends of the draft beam to the inner and outer beams, wheels connected to the inner and outer longitudinal beams, and means on each beam for raising and lowering the wheels whereby the beams and bars may be elevated for the purpose of conveying them from one destination to another.

12. A road drag comprising a frame, scrapers hinged at their inner ends to the sides of said frame, a manually operated device on the frame having connection with

the outer ends of the scrapers to swing the same into the desired angle, and a draft beam for the drag, said draft beam being adjustably connected to the frame and to the
5 outer ends of the scrapers to admit the free movement of the scrapers by said operating device during the travel of the drag.

In testimony, that I claim the foregoing as my own, I have hereto affixed my signature in the presence of two witnesses.

HILDOR ERICKSON.
